UNITED STATES PATENT OFFICE.

FREDERICK H. LEINWEBER, OF CHICAGO, ILLINOIS; CURTIS H. LEINWEBER, WILLIAM H. LEINWEBER, AND VICTOR H. LEINWEBER EXECUTORS OF SAID FREDERICK H. LEINWEBER, DECEASED.

INTERNAL-COMBUSTION ENGINE.

1,296,672.

Specification of Letters Patent. Patented Mar. 11, 1919.

Application filed November 6, 1916. Serial No. 129,871.

To all whom it may concern:

Be it known that I, FREDERICK H. LEINWEBER, a citizen of the United States, and a resident of the city of Chicago, county of 5 Cook, and State of Illinois, have invented certain new and useful Improvements in Internal-Combustion Engines, of which the following is a specification.

My invention relates to improvements in 10 internal combustion engines and more particularly to an improved valve arrangement and means for operating the same for exhausting said engine, the object of the invention being to provide such an improved 15 valve arrangement which is simple in construction and efficient in operation.

The invention consists in the combinations and arrangements of parts hereinafter described and claimed.

20 The invention will be best understood by reference to the accompanying drawings forming a part of this specification, and in which,

Figure 1 is a vertical section taken 25 through an engine equipped with valve mechanism, embodying my invention,

Fig. 2, a section taken on line 2—2 of Fig. 1,

Fig. 3, a side elevation, shown partially in 30 section, of the lower portion of the engine taken at right angles to Fig. 1,

Fig. 4, a section taken on line 5—5 of Fig. 1,

Fig. 5, a section taken on line 6—6 of 35 Fig. 1,

Fig. 6, a sectional view illustrating a modified form of valve construction.

The form of construction illustrated in Figs. 1 to 5 inclusive, comprises a closed 40 crank case 9 having a comparatively large cylinder 10 attached thereto. A piston 11 operates in cylinder 10 and is connected by means of a connecting rod 12 with a crank shaft 13 in crank case 9. A comparatively 45 small cylinder 14 is arranged coaxially with cylinder 10 and a piston cylinder 15 operates in cylinder 14, the same being connected with the piston 11, as shown. A stationary piston 16 is arranged to operate in piston 50 cylinder 15 in the usual manner as is more fully set forth in co-pending applications hereinafter mentioned and the cylinder 14 is provided with an inwardly extending head 55 equipped with spark plugs 18, the piston

cylinder 15 being also equipped with spark 55 plugs 19. The engine cylinders and coöperating parts thus far described are fully set forth and described in co-pending applications No. 127,291, filed October 23, 1916, and No. 129,870 filed November 6, 1916, and form 60 no part of the present invention, it being sufficient to say that cylinder 10, and piston 11, cylinder 14, piston cylinder 15, and stationary piston 16 are provided with suitable 65 passages and ports (not shown), whereby suitable charges of three different kinds of fuel are successively forced into the upper operative end of cylinder 14 for effecting operations of the engine. The present invention relates solely to the means employed 70 for controlling the exhaust valve of the engine, and is equally operative with other forms or arrangements of pistons and ports for forming and admitting the charges to 75 the engine.

The cylinder 14 is provided with a plurality of exhaust ports 20 in the outer walls thereof and a sleeve valve 21 is arranged to reciprocate in cylinder 14 and is provided with ports 22 arranged to register with ports 20 to effect exhaust of cylinder 14. The sleeve valve 21 is normally held in elevated or valve closing position by means of a compression spring 23, and the lower end of said sleeve valve is provided with an annular piston 24 operating in an annular cylinder 25 surrounding the engine cylinder 14 and formed by a sleeve 26 adjustably secured in position surrounding the lower portion of sleeve valve 21 and the corresponding portion of engine cylinder 14. A plurality of exhaust ports 27 are provided in the walls of sleeve valve 21 and a plurality of piston-controlled ports 25' are arranged to admit pressure from the engine cylinder 14 to the 85 upper end of cylinder 25, at or near the end of the operative stroke of piston cylinder 15, the arrangement being such that the high pressure generated in the upper end of engine cylinder 14 will thus serve to automatically open the exhaust valves 20 at or near the end of the operative stroke of piston cylinder 15. By adjusting the sleeve 26 vertically, the exhaust ports 27 may be arranged to be uncovered at different times in the 90 stroke of the sleeve valve 21 to exhaust the cylinder 25 as desired.

At its upper end the valve sleeve 21 is

provided with another annular piston 28 operating in an annular cylinder 29 surrounding the upper end of engine cylinder 14, which is extended for this purpose. Exhaust ports 30 are formed in the walls of cylinder 29 and vertical admission passages 31 are formed in the inner walls of valve sleeve 21 between ports 22, the lower ends of the passages 31 being provided with transverse extensions 32 arranged to communicate with the exhaust ports 20 upon initial downward movement of the sleeve valve 21. A guard sleeve 33 is adjustably secured to sleeve valve 21 to embrace the outer wall of cylinder 29 and control the ports 30 therein, a set screw 34 permitting of adjustment of said guard sleeve 33. Guard sleeve 33 is also provided with suitable exhaust openings registering with exhaust ports 22 in sleeve valve 21, as shown in Fig. 1, to permit of the free exhaust through said ports. By this arrangement, it will be observed that upon initial downward movement of the sleeve valve 21 under the influence of the combustion pressure in the engine cylinder 14, the combustion pressure in said cylinder will also be admitted to the cylinder 29 to complete the downward or operative movement of sleeve valve 21. By adjusting the guard sleeve 33 the exhaust of cylinder 29 may be regulated as desired.

In the modified form of construction illustrated in Fig. 6, a sleeve valve 35 is provided with ports 36 arranged to register with the exhaust ports 20 in cylinder 14, said sleeve valve being provided with guide rods 37 and compression springs 38, as indicated for normally holding the same in valve closing position and guiding the movements thereof. At its lower end the sleeve valve 35 is provided with an annular piston 39 operating in an annular cylinder 40 supplied with pressure from engine cylinder 14 by means of a piston-controlled port 40'. Cylinder 40 is provided with exhaust ports 41 controlled by an adjustable guard sleeve 42, as indicated. This furnishes a slightly different arrangement for controlling the exhaust of the cylinder by means of the internal pressure thereof.

In both of the constructions above described, air under pressure is supplied from cylinder 10 as is more fully set forth in co-pending applications. Cylinder 10 is provided with a plurality of ports 43 in the walls thereof and a sleeve 44 is made adjustable thereon to control said ports. If desired, the sleeve 44 may be connected with the sleeve 26 compelling simultaneously movements thereof. By this means the supply of compressed air supplied by cylinder 10 may be adjusted and when the sleeves are connected together the supply of compressed air may be regulated to correspond with the exhaust.

A passage 45 is arranged in the wall of cylinder 10 leading from the crank case 9 to a pipe 46 in the wall of cylinder 14. Another pipe 47 connects with a different passage 48 in the wall of cylinder 15 and it is designed that a carbureting arrangement (not shown) be attached to pipes 46 and 47, so as to carburize air passing from crank case 9 and into the cylinders, all as more fully described in my co-pending application, No. 127,291.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. The combination with an internal combustion engine cylinder having one or more ports in the walls thereof, of a sleeve valve controlling said ports; yieldable means for normally holding said sleeve in port-closing position; pressure operable means for operating said sleeve to open said port or ports; and means for exhausting said pressure operable means, substantially as described.

2. The combination with an internal combustion engine cylinder having one or more ports in the walls thereof, of a sleeve valve controlling said ports; yieldable means for normally holding said sleeve in port-closing position; pressure operable means for operating said sleeve to open said port or ports; and adjustable means for exhausting said pressure operable means, substantially as described.

3. The combination with an internal combustion engine cylinder having one or more ports in the walls thereof, of a sleeve valve controlling said ports; yieldable means for normally holding said sleeve in port-closing position; an annular cylinder surrounding said engine cylinder; an annular piston on said sleeve valve operating in said annular cylinder; a piston-controlled port adapted to admit pressure from said engine cylinder to said annular cylinder; and a piston-controlled port in said annular cylinder, substantially as described.

4. The combination with an internal combustion engine cylinder having one or more ports in the walls thereof, of a sleeve valve controlling said ports; a spring normally holding said sleeve in port-closing position; an annular cylinder surrounding said engine cylinder; an annular piston operating in said annular cylinder; a port controlled

by the piston in the engine cylinder for supplying pressure to said annular cylinder to give initial opening movement to said valve; an annular cylinder located adjacent the ports in the walls of the engine cylinder; an annular piston on said sleeve valve operating in said last mentioned annular cylinder; and passages in said sleeve valve arranged to communicate with said

ports after initial movement of said sleeve 10 valve, substantially as described.

In testimony whereof I have signed my name to this specification in the presence of two subscribing witnesses.

FREDERICK H. LEINWEBER.
